LOCOMOTIVE BOILER FIREBOX

Arthur W. Nelson, Park Ridge, Ill., assignor to
 Locomotive Firebox Company, Chicago, Ill., a
 corporation of Delaware

Application September 26, 1942, Serial No. 459,772

9 Claims. (Cl. 122—68)

This invention relates to improvements in locomotive boiler fireboxes and it consists of the matters hereinafter described and more particularly pointed out in the appended claims.

The invention is more especially concerned with locomotive boiler fireboxes of the kind equipped with the so-called "side sheet circulators" which are spaced longitudinally of the firebox and extend transversely thereof and each of which include tubular lower portions that open at one end through the side sheets of the firebox and one or more upper portions that are connected at one end to the lower portion and open at the top end through the crown sheet.

Among the objects of the present invention is to provide in a locomotive boiler firebox of the kind mentioned, simple and inexpensive and efficient means whereby a water circulation is established between the various elements, the evaporating surface of the firebox is increased, and at the same time the elements are connected together and braced against undesired movement longitudinally of the firebox.

The above mentioned objects of the invention, together with others, as well as the advantages thereof will more fully appear as the specification proceeds.

In the drawings:

Fig. 1 is a longitudinal vertical sectional view through a combustion type of locomotive boiler firebox embodying the preferred form of the invention.

Fig. 2 is a transverse vertical sectional view through a part of the boiler, on an enlarged scale, as taken on the line 2—2 of Fig. 1.

Fig. 3 is a detail longitudinal horizontal sectional view through Fig. 1 as taken on the line 3—3 thereof and on a scale enlarged thereover.

Fig. 4 is a fragmentary view of parts appearing in Fig. 2 and shows a modified arrangement therefor as will later be mentioned in more detail.

Fig. 5 is a vertical sectional view through parts appearing in Fig. 4 and as taken on the line 5—5 thereof.

Fig. 6 is a fragmentary view showing a modified form of arrangement of certain parts appearing in the upper left hand corner of Fig. 1.

Referring now in detail to that embodiment of the invention illustrated in Figs. 1, 2 and 3 of the drawings, the firebox therein shown comprises a crown sheet 5, which merges into the inner side sheets 6, the back sheet 7 and inner throat sheet 8. The crown sheet extends forwardly of the inner throat sheet 8 to form the top of the com-

bustion chamber 9. This chamber is closed at the front by a flue sheet 10 and the bottom 11 of said chamber merges into the front end of the inner throat sheet 8.

The outer rear sheet of the boiler is indicated at 12, the outer side sheets are indicated at 13 (see Fig. 2) and the outer throat sheet is indicated at 14. The said sheets 12—13 and 14 cooperate with the top sheet 15 of the boiler and with the inner sheets 5, 6, 7 and 8 in forming the back water leg 16, the side water legs 16a and the front throat 17 respectively, all in communication with the water space 18 of the boiler. The back and side water legs and the front throat are bottomed by a mud ring 19 and portions of the inner and outer back sheets are formed to coact in providing a conventional fuel door opening 20. The crown sheet and side sheets are connected to the top sheet 15 and to the outer side sheets 13 by staybolts 21 and these are disposed in rows extending longitudinally and transversely of the firebox as a whole. The structure just described is conventional in locomotive boiler type of firebox and requires no further detailed description.

To increase the effective evaporating surface of the firebox and the water steaming and circulating efficiency of the associated boiler, as well as to provide support for an arch in the firebox when such an arch is desired, the following arrangement is present:

In the firebox I provide one or more members, each having a lower portion that has its ends opening through the side sheets and a plurality of spaced apart upper portions that connect the said lower portion with the boiler water space above the crown sheet. The number of such members is, of course, dependent upon the size and type of firebox. As shown in Fig. 1, there are seven of such members spaced apart longitudinally of the firebox as a whole and extending transversely thereof, with five of such members disposed in the main fire chamber of the firebox, all of which are connected as hereinafter described, to constitute a unitary water steaming and circulating device or element. Disposed in the combustion chamber, there are shown two additional members. Beginning at the rear end of the firebox, these members bear the consecutive reference numerals 22—23—24—25—26—27 and 28 respectively.

All of these members are similar in structure and differ only in size, as manifested principally in the length of certain of the parts thereof. Therefore, a description of one member will suf-

fice for all. Taking the member 26 (see Fig. 2) in the main fire chamber as an example, merely because it has the greatest vertical height or length, the same includes a hollow lower portion in the form of a pair of outwardly and downwardly extending tubular inlet legs 29-29 respectively, the outer end of each of which opens through and is welded pressure-tight in an associated side sheet 6 of the firebox. 30-30 indicate the upwardly extending tubular outlet legs of the member, the lower ends of which curve inwardly toward each other to connect with the top central part of a junction portion 31, the bottom part of which is in communication with the top central part of the inlet legs 29-29. If desired, but not necessarily so, as far as the present invention is concerned, I may provide an upright partition 32 in the junction portion 31 of each member to divide the same into two channels 33-33 each connecting an inlet leg 29 with an outlet leg 30 on the same side of the partition.

Cross reference is hereby made to my co-pending application filed September 26, 1942, Serial No. 459,771, which discloses and claims certain of the features which are herein disclosed but not claimed.

To establish a circulation between certain of the members and especially between those in the main fire chamber of the firebox, as well as to increase the evaporating surface thereof, and at the same time to provide a bracing between said members longitudinally of the firebox, I provide the following constructions: Between each two adjacent members in the main fire chamber, I provide one or more longitudinally extending tubes, which are fixed pressure-tight, as by welding, at their ends in parts of said adjacent members. In Figs. 2 and 3, I have shown two of such tubes 34-34, as extending longitudinally between each two adjacent members in the main fire chamber. When two of such tubes are employed, they are disposed one on each side of the plane of the partitions 32 in said adjacent members, each with their ends opening into the inner end of the associated inlet legs and at a point substantially disposed slightly below the junction portion 31 of said member. These tubes 34-34 provide for the establishment of a water circulation between said members as well as providing additional evaporating surface. They also connect and brace the lower central portions of the members longitudinally of the firebox, thus uniting the members into an integral whole well adapted to withstand the strains and stresses to which the device is subjected in use.

Preferably I provide similar tubes between the frontmost and the rearmost members 26 and 22 and adjacent parts of the firebox and in the present instance tubes 35 connect the front side of the front member 26 with the top of the inner throat sheet, and tubes 36 connect the rear side of the rear member 22 with the rear sheet 7 of the firebox. Washout plugs 37 are preferably provided in the sheets 12 and 14 in line with the tubes 36 and 35, respectively, all as best appears in Fig. 1.

Instead of the tubes 36 opening through the back sheet 7, they may open through the crown sheet as at 36x as best appears in Fig. 6, other parts in said figure similar to those appearing in Fig. 1 bearing the same reference numerals as in Fig. 1.

In lieu of employing two of such tubes between each two adjacent members, I may use only one

of them as appears in Fig. 4. Under such condition, the tube, which is indicated at 37 is preferably of a diameter larger than the tubes 34 and it is disposed with its axis in the plane of the partition 38 in said adjacent members. To prevent the water in the inlet legs of each member from by-passing from one side to the other of the partitions, I provide said partitions with extension pieces 39 (see Fig. 5) which project a short distance into the ends of the tubes 37.

When an arch is desired in the firebox, a series of side bricks 40 (see Figs. 1 and 2) is laid upon the inlet legs 29-29 of the members in the main fire chamber, with the ends of said bricks, considered longitudinally, engaged upon said legs. The innermost bricks of the same set are separated to provide a space in the plane of the junction portions of the members and this space is filled in by a central key brick 41 that has a wedge-like engagement at its sides with said innermost bricks as best appears in Fig. 2. It is to be noted from Figs. 2 and 4 respectively that the center or key bricks extend over the tubes 34-34 and 37.

With the arrangement of parts as described, the said tubes, just above mentioned, provide a water circulation between said members. Said tubes also increase the evaporating surface of the firebox as a whole and at the same time connect said elements together so that they brace one another longitudinally of the firebox.

The members 27 and 28 in the combustion chamber may be connected by one or more tubes 34c as shown, thus uniting them into a single or unitary water circulating and steaming element or device. One end of a tube 34d is connected to one of said members 27-28 and its other end opens through the bottom 11 of the combustion chamber 9 while one end of another tube 34e is connected to the other of said members and its other end opens through the crown sheet.

While in describing the invention I have referred in detail to the form, arrangement and construction of the parts involved, the same is to be considered only in the illustrative sense so that I do not wish to be limited thereto except as may be specifically set forth in the appended claims.

I claim as my invention:

1. In combination with a locomotive boiler firebox embodying therein a crown sheet and side sheets, a plurality of longitudinally spaced water steaming and circulating members in the firebox, each member comprising a lower portion that extends transversely of the firebox and has its ends opening through the side sheets and an upper portion connecting said lower portion with the water space of the boiler above the crown sheet, bricks supported upon the lower portion of said members to provide a fire arch in the firebox, and means arranged below and in non-supporting relation with respect to said arch and extending longitudinally of the firebox, for providing a water communication between adjacent members and connecting them so they constitute a unitary water circulating and steaming device.

2. In combination with a locomotive boiler firebox embodying therein a crown sheet and side sheets, a plurality of longitudinally spaced water steaming and circulating members in the firebox, each member comprising a lower portion that extends transversely of the firebox and has its ends opening through the side sheets and an upper portion connecting said lower portion with

the water space of the boiler above the crown sheet, and means extending longitudinally of the firebox, providing a water communication between the lower portions of adjacent members, at an elevation above the ends thereof and connecting them so they constitute a unitary water circulating and steaming device.

3. In combination with a locomotive boiler firebox embodying therein a crown sheet, a front throat sheet and side sheets, a plurality of longitudinally spaced transversely extending water steaming and circulating members in the firebox, each member comprising a lower portion having ends opening through the side sheets and a plurality of spaced upper portions each opening separately through the crown sheet and connecting said lower portion with the boiler water space above the crown sheet, means extending longitudinally of the firebox and providing a water communication between parts of adjacent members below the upper portions thereof and connecting them so they constitute a unitary water circulating and steaming device, and a tubular member opening at one end into the frontmost water steaming and circulating member and opening at its other end through said throat sheet.

4. In combination with a locomotive boiler firebox embodying therein a crown sheet and side sheets, a plurality of longitudinally spaced water steaming and circulating members in the firebox, each comprising lower portions that extend transversely of the firebox and a plurality of spaced upper portions each opening at the upper end through the crown sheet and connected by a junction portion to the associated lower portions, and means extending longitudinally of the firebox and providing a water communication between parts adjacent the junction portions of adjacent members and connecting them so they constitute a unitary water circulating and steaming device.

5. In combination with a locomotive boiler firebox embodying therein a crown sheet and side sheets, a plurality of longitudinally spaced water steaming and circulating members in the firebox, each comprising lower portions that extend transversely of the firebox and a plurality of spaced upper portions each opening at the upper end through the crown sheet, and connected to said lower portions by a junction portion divided into non-communicating passageways, each in separate communication with an upper and a lower portion relatively, and tubular means extending longitudinally of the firebox and affording communication between the passageways of one member with the passageways in an adjacent member and connecting said members so they constitute a unitary water circulating and steaming device.

6. In combination with a locomotive boiler firebox embodying therein a crown sheet and side sheets, a plurality of longitudinally spaced water steaming and circulating members in the firebox, each comprising lower portions that extend transversely of the firebox, and a plurality of

spaced upper portions each opening at the upper end through the crown sheet, and connected to said lower portions by a junction portion divided into non-communicating passageways, each in

5 separate communication with an upper and a lower portion relatively, and a tubular member extending longitudinally of the firebox and affording communication between the passageways of one member with the passageways of an adjacent member, and connecting said members so they constitute a unitary water circulating and steaming device.

7. In combination with a locomotive boiler firebox embodying therein a crown sheet and side sheets, a plurality of longitudinally spaced water steaming and circulating members in the firebox, each comprising lower portions that extend transversely of the firebox and a plurality of spaced upper portions each opening at the upper end through the crown sheet, and connected to said lower portions by a junction portion divided into non-communicating passageways, each in separate communication with an upper and a lower portion relatively, and tubular means extending longitudinally of the firebox and connecting said members at the junction portion thereof as a unitary water steaming and circulating device, said tubular means having an operative connection with a part of the water space of the boiler spaced from said members.

8. In combination with a locomotive boiler firebox embodying therein a crown sheet and side sheets, a plurality of longitudinally spaced water steaming and circulating members in the firebox, each comprising lower portions that extend transversely of the firebox and a plurality of spaced upper portions, each opening at the upper end through the crown sheet, and connected to said lower portions by a junction portion, means 35 in each junction portion dividing the same into non-communicating passageways, each in separate communication with an upper and a lower portion respectively, and a tube extending longitudinally of the firebox and bracing and connecting the junction portion of one member with the junction portion of an adjacent member, said means in said junction portion of one member having portions extending into each tube connected therewith for preventing water communication between said passageways of said member.

9. In combination with a locomotive boiler firebox embodying therein a crown sheet and side sheets, a plurality of longitudinally spaced water steaming and circulating members in the firebox, each comprising lower portions that extend transversely of the firebox and a plurality of spaced upper portions each opening at the upper end through the crown sheet and connected by a junction portion to the associated lower portion, bricks supported upon the lower portions of the respective elements to provide a fire arch in the firebox, and means extending longitudinally of the firebox below said arch and providing a water communicating and bracing connection 55 between adjacent elements.

ARTHUR WM. NELSON.
